AIR INSULATED VALVE AND GUIDE FOR INTERNAL COMBUSTION ENGINES

Victor F. Zahodiakin, New York, N. Y.

Application July 2, 1936, Serial No. 88,644

6 Claims. (Cl. 123—188)

This invention relates to internal combustion engines and is particularly directed to improvements in the exhaust valves and exhaust valve guides thereof.

The modern engine operates at exceptionally high speed and at high compression. Accordingly, the valves must operate extremely efficiently since they play the most important and vital part in the operation of the engine. The fuels or hydrocarbons used in the modern engine, such as ethyl gasoline, produce excessive carbon formations on the exhaust valve stems, which formations interfere with the operation of the valves causing sticking and ultimate burning thereof.

It is the object of the present invention to provide an improved exhaust valve and guide therefor, adapted for use in an internal combustion engine, which eliminate excessive formations or deposits of carbon on the valve stems, thus preventing the usual interference with free operation and thereby eliminating sticking. Accordingly, by the use of the valves and guides of this invention, the efficiency of the valves will not be impaired and the normal power of the engine will be maintained.

In a more refined sense, it is the object of the present invention to provide for the guides and valves a new arrangement and structure which create an air chamber in combination with the valve stem, insulating the valve stem from the effects of the heat, thus materially reducing the operating temperature of the valve and increasing the efficiency of valve operation.

Other objects and certain advantages will be more fully apparent from a description of the accompanying drawing, in which:

Figure 1 is a fragmentary sectional view of a portion of an internal combustion engine at the point of the exhaust valve, showing the exhaust valve in closed position.

Figure 2 is a sectional view taken similar to Figure 1, but showing the valve in open position.

Figure 3 is a sectional view taken similar to Figure 1, showing the valve in closed position in conjunction with a modified type of guide.

Figure 4 is a sectional view taken similar to Figure 1, showing a still further modification of the valve and guide with the valve in closed position.

Referring to the structure disclosed in Figures 1 and 2, the cylinder block is generally indicated at 10, the cylinder head at 11, one of the cylinders at 12, and the piston at 13. The exhaust passageway, indicated at 14, extends from the

combustion chamber 9 laterally of the cylinder block in the usual manner.

The improved valve 15 is slidably mounted in an improved guide 16 and is seated on a valve seat 8. The diameter of the valve stem is reduced close to the head, as at 17. The valve stem extends across the exhaust passageway to a point immediately adjacent to the rear side of the head of the valve. The internal or guide bore of the guide is annularly grooved as at 18 to provide an elongated chamber which extends substantially from the plane of the lower wall of the exhaust passageway to the upper end of the guide, stopping short sufficiently of the upper end of the guide to provide a closed upper end for the chamber. Thus an air chamber is constituted which serves as an insulator for the valve stem preventing overheating thereof.

The structural arrangement of the guide relative to the valve stem, substantially completely encasing the valve stem seals the valve stem from the exhaust passageway and prevents any accumulation or deposit of carbon on the valve stem. The reduced portion 17 provides a shoulder 19 which acts as a scraping edge for constantly scraping the carbon from the straight upper guide portion of the guide. Each time the valve is closed this edge moves down below the top edge of the guide but no lower than midway of the guide portion of the guide. Each time the valve raises or unseats, the edge scrapes any accumulation of carbon from the guide portion.

As the valve begins to close each time, the sharp upper edge 7 of the valve guide will scrape, from the valve stem, any formations of carbon which may have been deposited thereon during the exhaust stroke of the piston. This constant removal of carbon, not only from the valve stem but from the guide portion of the guide, prevents any accumulation of carbon and insures a free working valve. It will be observed that only a small portion of the valve stem is momentarily in contact with the discharge gases during the exhaust stroke of the piston. Consequently the valves will not be damaged by overheating and there will be no interference with normal operation of the engine.

Referring to the modified form of the invention in Figure 3, the corresponding parts will be found to be identified by the same numerals as those employed in the preceding form. In this case the valve stem is perfectly plain, there being no reduction of diameter. The valve guide extends into very close proximity to the back of the valve head as in the preceding instance. The

guide bore of the guide is counterbored as at 20 to provide an air space or annular chamber for insulation of the valve stem from the effects of hot gases passing through the exhaust passage- 5 way.

This counterbored portion is tapered or enlarges toward the top of the guide. Any carbon deposits which may take place will occur toward the upper end of the valve stem, that is, adjacent the head. Accordingly, due to the enlargement of the bore, ample clearance is provided in order that operation of the valve stem may not be interfered with. There is no opportunity for carbon deposit far down in the 15 chamber since a back pressure of air is built up in this chamber effectively blocking the entrance of carbon to the lower end of the chamber where it might tend to enter the guide bore portion 21. This air chamber just as the chamber in the 20 preceding form acts as an insulator and prevents overheating of the valve and stem.

In the modification disclosed in Figure 3, the parts corresponding to those of the preceding forms are identified by similar numerals. A 25 counterbore is provided in the guide bore of the guide, as indicated at 22, the counterbore being straight in this instance and slidably receiving an enlarged straight cylindrical portion 23 of the valve stem. The portion 23 is disposed adjacent 30 the head of the valve, the upper edge or shoulder thereof being in the same relation to the upper end of the valve guide as the shoulder 19 of the form shown in Figures 1 and 2. For this reason the same scraping action takes place in this 35 form.

The portion 23 acts as a plug for the upper end of the chamber 22, and this chamber is therefore effective as an insulating chamber in the manner and for the purposes previously described. 40 The portion 23 is of sufficient length so that its lower edge will not rise above the upper edge of the valve guide in the opening motion of the valve. Accordingly, the chamber is always sealed.

Longitudinal grooves 24 extend from the base 45 of the chamber 22 along the internal bore of the guide to the extreme lower end thereof. These grooves permit the expulsion of air from the insulation chamber on the closing movement of the valve and permit intake of cooler air from the 50 lower outer end of the valve guide into the chamber as the opening movement of the valve takes place. Thus the air in the insulation chamber is constantly replenished, cool air replacing the heated air which results from the passage of the 55 hot gases around the valve guide. Thus a constant cooling circulation ensues with the valve acting as a pump.

In all forms of the valve guide it will be noted that the upper portion thereof tapers toward the 60 upper edge thereof. The gradual increase in cross sectional area of the guide from the upper end downwardly provides the proper structure for heat dissipation. The tapering of the structure and reduction in mass toward the upper 65 end of the valve guide is doubly true in the form of Figure 3 since the counterbored portion of the internal bore of the guide flares upwardly.

Having described my invention, I claim:

1. In an internal combustion engine including a 70 cylinder block and head, said parts including an exhaust passageway incorporating a valve seat, a valve guide element mounted in the cylinder block and extending to a point just below the valve seat, a valve slidably mounted in said guide for engagement on said seat and including a por- 75

tion of reduced diameter immediately adjacent its head, the shoulder between the reduced diameter portion and the body of the stem disposed within the upper end of the valve guide when the valve is seated and adapted to scrape any 5 carbon deposits from the upper end of the valve guide upon the opening movement of the valve, said valve guide including a counterbored portion terminating slightly below the outer end of the 10 valve guide and extending along that portion of the valve guide disposed across the exhaust passageway, thereby providing an insulating chamber. 15

2. In an internal combustion engine including a cylinder block and head thereof, said parts 15 including an exhaust passageway incorporating a valve seat, a valve guide element mounted in the cylinder block and extending to a point just below the valve seat, a valve slidably mounted in said guide and adapted to engage said seat, the stem of said valve including a portion of reduced diameter immediately adjacent its head, a shoulder between the reduced diameter portion and the body of the stem disposed within the upper end of the valve guide when the valve is seated and adapted to scrape any carbon deposits from the upper end of the valve guide as the opening movement of the valve takes place and the upper end edge of the valve guide bore adapted to scrape any carbon deposits from the portion of the valve stem which is exposed to the 25 exhaust gases when the valve is opened. 30

3. In an internal combustion engine including an engine body consisting of a block and head including an exhaust passageway therein and a 35 valve seat in the exhaust passageway, a valve guide disposed across the exhaust passageway and having its upper end adjacent the valve seat, a valve slidably mounted in the guide and having a head adapted to engage the valve seat, said 40 valve guide having an enlarged bore portion along that portion extending across the exhaust passageway, and the stem of said valve including an enlarged portion adjacent the head thereof but spaced therefrom, said latter portion slidably mounted in the counterbored portion of the 45 guide, and passageways disposed along the guide bore connecting the lower end of the enlarged bore portion with the lower end of the valve guide for air circulation to and from the chamber formed by the enlarged bore portion. 50

4. In an internal combustion engine including the engine body consisting of a cylinder block and head and incorporating an exhaust passageway having a valve seat therein, a valve guide 55 mounted in the body and having a portion extending across the exhaust passageway to a point adjacent the valve seat, a valve slidably mounted in the guide element and adapted to engage said seat, said guide having its internal 60 bore counterbored to provide an annular insulation chamber surrounding the valve stem, and a cool air inlet to said chamber. 65

5. In an internal combustion engine including an engine body consisting of a block and head including an exhaust passageway therein and a valve seat in the exhaust passageway, a valve guide disposed across the exhaust passageway and having its upper end adjacent the valve seat, a valve slidably mounted in the guide and having a head adapted to engage the valve seat, said valve guide having an enlarged bore portion along that portion extending across the exhaust 70 passageway, and the stem of said valve including an enlarged portion adjacent the head thereof 75

but spaced therefrom, said latter portion slidably mounted in the counterbored portion of the guide, and said guide including passageways disposed along the guide bore connecting the lower end 5 of the enlarged bore portion with the lower end of the valve guide for air circulation to and from the chamber formed by the enlarged bore portion, said enlarged portion of the valve stem serving as a pumping piston for said chamber.

10 6. In an internal combustion engine including a cylinder block and head thereof, said parts including an exhaust passageway incorporating a valve seat, a valve guide element mounted in the cylinder block and extending to a point just 15 below the valve seat, a valve slidably mounted in said guide and adapted to engage on said

seat, the stem of said valve including a shoulder disposed immediately adjacent to the valve head and within the upper end of the valve guide when the valve is seated and adapted to scrape any carbon deposits from the upper end of the valve guide on the opening movement of the valve, said valve guide element and said valve stem providing a closed insulation chamber around the valve stem extending along the valve stem across the exhaust passageway, and the 10 upper end edge of the guide bore adapted to scrape any carbon formations from the exposed part of the valve stem which is above the edge when the valve is opened.
